[57] CLAIM

The ornamental design for a frame for a racing cart, as shown and described.

DESCRIPTION

FIG. 1 is a perspective view of a frame for a racing cart as viewed toward the front, top and one side thereof, showing our new design;

FIG. 2 is a perspective view, as viewed toward the back and opposite side thereof; and

FIG. 3 is a bottom perspective view thereof.

FIG. 2

FIG. 3
